FLUID PRESSURE CONTROL DEVICE

Ludwig A. Majneri, Grosse Pointe, Mich., assignor
to The Warner Aircraft Corporation, Detroit,
Mich., a corporation of Michigan

Application September 14, 1942, Serial No. 458,264

9 Claims. (Cl. 60—54.6)

The invention relates to fluid pressure control devices and refers more particularly to fluid pressure control devices for hydraulic brakes.

The invention has for one of its objects to provide an improved fluid pressure control device of the compound type having a low pressure producing means and a high pressure producing means adapted to operate successively in producing fluid pressure.

The invention has for another of its objects to provide an improved mechanism for controlling the change-over from the effective operation of the low pressure producing means to the effective operation of the high pressure producing means during the advance or pressure stroke of the device.

The invention has for other objects to provide the change-over controlling mechanism with a valve and with adjustable means for controlling the movement of the valve; to provide the change-over controlling mechanism with means for limiting movement of the valve to secure approximately the same effective advance or pressure stroke regardless of the speed of advance; to provide the change-over controlling mechanism with means for resiliently opposing movement of the valve in a manner to approximately compensate for different brake characteristics; to provide the change-over controlling mechanism with means for opposing movement of the valve approximately in accordance with the viscosity of the fluid; and to provide the change-over controlling mechanism with a plunger for operating the valve and with means engageable with the plunger to oppose a resistance to its movement.

The invention has for further objects to provide a fluid pressure control device in which the low pressure producing and the high pressure producing means comprise low pressure and high pressure cylinders and pistons slideable within the cylinders and adapted to be directly moved from off position by a piston rod which serves to conduct fluid from the high pressure cylinder to hold a valve in open position and thereby allow fluid in the low pressure cylinder to flow to a reservoir, whereby the low pressure cylinder is relieved; and to provide in the fluid pressure control device a plunger subject to the pressure of the fluid in the high pressure cylinder for holding the valve in open position.

With these and other objects in view, the invention resides in the novel features of construction and combinations and arrangements of parts as more fully hereinafter set forth.

In the drawings:

Figure 1 is a vertical central section through a fluid pressure control device embodying my invention;

5 Figure 2 is a similar view showing the parts in a different position during the operation of the device;

Figures 3 and 4 are cross sections on the lines 3—3 and 4—4, respectively, of Figure 1;

10 Figures 5 and 6 are views similar to Figures 1 and 2, respectively, showing another embodiment of the invention;

Figure 7 is a view similar to a portion of Figure 1 showing another embodiment of the invention.

15 The fluid pressure control device is particularly applicable to a hydraulic brake system of an airplane, but it is apparent that the device may be used with other hydraulic brake systems. While the devices, as shown, do not incorporate the 20 parking features of my Patent No. 2,115,174, issued April 26, 1938, or my Patent No. 2,120,073, issued June 7, 1938, the parking features may be readily incorporated in accordance with the teachings of the patents.

25 The fluid pressure control device generally comprises high pressure producing means, low pressure producing means, a reservoir, and mechanism for controlling the change-over from the effective operation of the low pressure producing 30 means to the effective operation of the high pressure producing means during the advance or pressure stroke of the device. As illustrated, the device occupies a substantially vertical position and comprises a high pressure chamber in its lower

35 portion, a low pressure chamber above the high pressure chamber, and a reservoir above the low pressure chamber and in the upper portion of the device. The high pressure chamber is adapted to discharge fluid under pressure through a discharge port which is adapted to be connected by tubing to a wheel cylinder for actuating a brake.

40 The low pressure chamber is adapted to discharge fluid under pressure to the high pressure chamber until a predetermined pressure of fluid in the low 45 pressure chamber is created, at which time the change-over controlling mechanism places the low pressure chamber in communication with the reservoir. Then when a predetermined pressure of fluid in the high pressure chamber is created, the fluid in the high pressure chamber operates upon the change-over controlling mechanism to hold the low pressure chamber in communication with the reservoir independently of the fluid in the low pressure chamber.

55 Referring to Figures 1 to 4, inclusive, the fluid

pressure control device has the lower high pressure cylinder 1, the upper low pressure cylinder 2 of larger diameter than the high pressure cylinder, and the braking fluid reservoir 3 above the low pressure cylinder. The fluid pressure control device also has the high pressure and low pressure pistons 4 and 5, respectively, slideable in the high pressure and low pressure cylinders, and the piston rod 6 operatively connected to the pistons and extending axially through the lower end of the high pressure cylinder. The high pressure cylinder is closed at its lower end by the plug 1 and the sealing cup 8, through both of which the piston rod 6 axially extends. The plug is fixedly secured in the lower end of the high pressure cylinder by suitable means and, as shown, is threaded at 9 into the high pressure cylinder. The high pressure cylinder is provided near its lower end with the discharge port 10 which is adapted to be connected to a wheel cylinder for actuating a brake by the usual tubing (not shown). The reservoir 3 is closed at its upper end by the upper end fitting 11 fixedly secured to the reservoir. The fitting has the depending annular flange 12 which is preferably threaded into the reservoir and which is provided with the external annular groove 13 and the radial passageways 14 leading from the groove to the chamber within the annular flange. The groove opens into the port 15 which is adapted to be connected to an auxiliary braking fluid reservoir. 16 is a sealing ring above the annular groove for preventing the leakage of braking fluid from the reservoir past the fitting.

The piston rod 6 is constructed to be pivotally connected to a suitable foot pedal for longitudinally moving the piston rod downwardly to operate the control device. The fitting 11 is provided with a suitable bushing 17 for engaging a pivot pin of a suitable support.

The lower high pressure piston 4 has the annular head 18 slideable within the high pressure cylinder 1 and the upwardly extending sleeve 19 formed of the reduced portion 20 and the enlarged portion 21. The upper end of the reduced portion has the annular valve seat 22 and the lower end of the enlarged portion has the transverse ports 23. The piston rod 6 slidably extends through the annular head and sleeve. The high pressure piston also has the annular sealing cup 24 preferably formed of rubber and provided with concentric lips for slidably engaging the wall of the high pressure cylinder 1 and the piston rod 6. The head 18 is formed with the transverse ports 25 for permitting the flow of the braking fluid from the low pressure cylinder to the high pressure cylinder. A resilient thin sheet metal disc 24' is preferably provided between the head 18 and the sealing cup 24 to prevent the latter from being forced into the transverse ports 25. Also a circular cross sectioned ring 24² preferably formed of rubber is preferably provided between the head 18 and the piston rod 6 to prevent the flow of the braking fluid therebetween. During the flow of the braking fluid from the low pressure cylinder to the high pressure cylinder through the transverse ports both the resilient disc and the sealing cup are flexed. The low pressure piston 5 has the body 26 and the annular head 27 which are fixedly secured to the upper end of the enlarged portion 21 of the sleeve of the high pressure piston. As shown, the body 26 is threaded into the upper end of the enlarged portion 21 and has the annular flange 28 which extends over and clamps the annular head 27 against the annular

shoulder 29 formed on the enlarged portion 21. I preferably provide the sealing ring 30 between the annular flange and head. The low pressure piston also has the flanged sealing ring 31 preferably formed of rubber and abutting the lower side of the head 27 and provided with an outer lip which slidably engages the wall of the low pressure cylinder 2. The sealing ring is clamped by the head 27 against the annular shoulder 32 formed on the enlarged portion 21 of the sleeve of the high pressure piston. The head 27 is formed with the transverse ports 33 for permitting the flow of braking fluid from the reservoir to the low pressure cylinder, during which time the sealing ring 31 is flexed.

The piston rod 6 has at its upper end the enlarged cup-shaped portion 34 which is located within the enlarged portion 21 of the high pressure piston sleeve. The bottom of the cup-shaped portion is provided with the annular ring 35 preferably formed of rubber and constituting a valve which is adapted to seat on the valve seat 22. The piston rod is provided with the axial passageway 36 and the radial passageways 37 and 38 leading from the axial passageway, the passageways 37 being below the sealing cup 24 and the passageways 38 being immediately below the valve 35. 39 is a retracting coil spring for resiliently holding the piston rod 6 in its off position. This coil spring abuts the sealing cup 8 and the annular shoulder 40 formed upon the annular wall 41 of the cup-shaped retainer 42. The retainer is held from upward movement relative to the piston rod by suitable means, such as the C-washer 43 within the retainer and engaging an annular groove in the piston rod. To prevent sticking of the sealing cup 24 during the return of the pistons to their off position, the annular wall 41 extends upwardly between the lips of the sealing cup to a zone adjacent the base of the sealing cup. The upper end of the annular wall is slotted so that the axial passageway of the piston rod is always in communication with the high pressure cylinder. 44 is a second retracting spring located between the low pressure piston and the piston rod for resiliently holding both the low pressure piston and the high pressure piston in their off position. As shown, the retracting spring 44 is a coil spring abutting the body 26 of the low pressure piston and the nut 45 which is threaded into the upper end of the enlarged cup-shaped portion 34 of the piston rod.

With the parts as thus far described, the high pressure piston and the low pressure piston are fixedly connected to each other and move in unison. Downward movement of the piston rod 6 through its valve 35 abutting the seat 22 advances both pistons and the piston rod and both pistons and the piston rod are adapted to be retracted to their off position by the coil springs 39 and 44. The coil spring 39 acts upon the piston rod to retract the same and the coil spring 44 acts upon the pistons to retract the same. The off position of the pistons is determined by abutment of the annular head 27 of the low pressure piston with the lower end of the annular flange 12 of the upper end fitting 11, while the off position of the piston rod is determined by the change-over controlling mechanism which is later described and which positions the piston rod relative to the pistons so that the valve 35 is spaced from the valve seat 22, at which time the high pressure cylinder is in communication with the low pressure cylinder. It will be noted that during the advance of the pistons braking

fluid is discharged from the low pressure cylinder into the high pressure cylinder through the ports 25 and past the resilient disc 24' and the sealing cup 24 and that during the retraction of the piston rod and pistons braking fluid may pass from the high pressure cylinder to the low pressure cylinder through the passageways 37, 36 and 38 of the piston rod between the separated valve 35 and seat 22 and through the ports 23 in the high pressure piston sleeve. Braking fluid may also pass from the reservoir to the low pressure cylinder through the ports 33 in the head 27 of the low pressure piston and past the sealing ring 31.

To relieve the fluid pressure in the low pressure cylinder during the advance or pressure stroke of the fluid pressure control device, I have provided a change-over controlling device for placing the low pressure cylinder in communication with the reservoir. The mechanism is first operated by the fluid in the low pressure cylinder to open the communication and then operated by the fluid in the high pressure cylinder to hold the communication open, thereby completely relieving the fluid in the low pressure cylinder from pressure except that of the hydraulic head of the fluid in the reservoir.

In detail, the body 26 of the low pressure piston is annular and provides an axial passageway 46 therethrough, the upper portion of which is enlarged. The upper portion of the annular flange 28 of the body is provided with the aligned radial grooves 47 for placing the enlarged portion of the axial passageway in communication with the reservoir. To place the reduced portion of the axial passageway in communication with the low pressure cylinder, I have provided the radial passageways 48 in the enlarged portion 21 of the high pressure piston sleeve and the external annular groove 49 in the body 26 registering with the radial passageways 48 and also the radial passageways 50 in the body 26 leading from the annular groove to the axial passageway. 51 is a ball valve within the enlarged portion of the axial passageway 46 and adapted to seat upon the annular seat 52 which is formed in the body 26.

For unseating the ball valve or raising it from its seat, I have provided the plunger 53 having its upper end engageable with the ball valve and its lower end registering with the axial passageway 36 in the piston rod and adapted to abut the bottom of the cup-shaped enlargement 34. The axial passageway is extended upwardly above the radial passageways 38 to open into the space formed within the cup-shaped enlargement so that the lower end of the plunger is subject to the braking fluid under the same pressure as that in the high pressure cylinder. 54 is a sealing ring within the cup-shaped enlargement 34 and having its base held against the nut 45 by the spacer 55. The sealing ring is channel-shaped in cross section and has an outer lip engaging the annular wall of the cup-shaped enlargement 34 and an inner lip engaging the plunger 53 which extends through and slidably engages the nut 45. The length of the plunger 53 is such that when the piston rod and the pistons are in off position the piston rod abuts the plunger and it, in turn, abuts the ball valve and holds the same off its seat. However, as soon as the piston rod is advanced to engage its valve 35 with the valve seat 22 the plunger is lowered and the ball valve engages its valve seat.

For guiding and controlling the movement of the ball valve, I have provided the plunger 56 hav-

ing a depending annular flange extending freely within the enlarged portion of the axial passageway 46 of the low pressure piston and encircling the ball valve 51 and having its body engageable with the ball valve. The bottom of the plunger is resiliently held against the ball valve by the coil spring 57 which at its lower end abuts the yoke or bar 58 secured to the plunger as by extending diametrically therethrough in registration with the grooves 47. The upper end of the coil spring abuts the collar 59 which is mounted on the annular flange 60, which latter extends upwardly from the annular body 26 of the low pressure piston and, more particularly, the annular flange 28 of the body. The collar is adjustably threaded on the annular flange to allow change of pressure of the spring for resiliently holding the ball valve in closed position to thereby approximately compensate for the different characteristics of the various brakes with which the fluid pressure control device may be used so that uniform braking action may be secured. To oppose movement of the ball valve approximately in accordance with the viscosity of the braking fluid, the plunger 56 is constructed to cooperate with the cylinder 61 in a manner to effect a dashpot action. The plunger slidably engages the cylinder and, as shown, is provided with the series of passageways 62 extending longitudinally through the body. To limit the movement of the ball valve to secure approximately the same effective advance or pressure stroke of the pistons regardless of the speed of advance, the dashpot cylinder 61 is formed with the annular stop 63 which is engageable with the upper end of the plunger. The cylinder is adjustably mounted on the low pressure piston as by being threaded into the annular flange 60. To lock the collar 59 and the dashpot cylinder 61 in their various adjusted positions, I preferably longitudinally slot the annular flange 60 in registration with the radial grooves 47, longitudinally slot the upper end/portion of the dashpot cylinder 61 and form openings in the collar 59 to receive a lock wire 64. The coil spring 57 is of a strength sufficient to hold the ball valve 51 to its seat 52 against the effort exerted by the braking fluid in the low pressure cylinder 2 until a pressure of the braking fluid predetermined by the adjustment of the collar 59 is created. However, the strength of the coil spring is less than that of the retracting coil spring 39 so that in the off position of the piston rod the ball valve will be unseated. Also, the force exerted by the coil spring is less than that adapted to be exerted by the braking fluid in the high pressure cylinder when it reaches a predetermined pressure during the operation of the pressure control device so that the coil spring yields to permit the ball valve to become unseated.

It will be noted that the off position of the piston rod 6 is determined by the dashpot cylinder 61 which is adjustably carried by the low pressure piston 5. The dashpot cylinder 61 abuts the dashpot plunger 56, which is engaged by the ball valve 51, which latter in turn is engaged by the plunger 53 held upwardly by the piston rod by means of the retracting spring 39.

Assuming the parts to be in the off position, as shown in Figure 1, the high pressure cylinder 1 is in communication with the low pressure cylinder 2 and the low pressure cylinder 2 is in communication with the reservoir 3. Upon downward pull of the piston rod 6, its valve 35 will seat upon the valve seat 22 to close communica-

tion between the high pressure cylinder 1 and the low pressure cylinder 2 through the piston rod. At the same time, the spring 57 seats the ball valve 51 upon its seat 52 to close communication between the low pressure cylinder 2 and the reservoir 3. Continued downward movement of the piston rod 6 compels the high pressure piston 4 and the low pressure piston 5 to move downwardly in unison during which time the braking fluid under pressure is forced from the low pressure cylinder 2 through the ports 25 and past the resilient disc 24 and sealing cup 24 into the high pressure cylinder 1 and the braking fluid in the latter cylinder is discharged through the discharge port 10. However, when pressure of the braking fluid within the low pressure cylinder 2 reaches a predetermined point, the braking fluid in the low pressure cylinder unseats the ball valve 51, thereby placing the low pressure cylinder in communication with the reservoir 3. Then when the pressure of the braking fluid within the high pressure cylinder 1 reaches a higher predetermined point the braking fluid within the axial passageway 36 in the piston rod acts upon the plunger 53 to hold the same against the ball 51 in open position, thereby completely relieving the braking fluid in the low pressure cylinder from pressure except that of the hydraulic head of the braking fluid in the reservoir. The unseating of the ball valve 51 takes place against the effort exerted by the coil spring 57 and the resistance offered by the dashpot cylinder 61 and dashpot plunger 56. The sealing ring 54 opposes frictional resistance to the unseating movement of the plunger 53 to hold the plunger from movement until the pressure of the braking fluid in the high pressure cylinder is higher than the pressure of the braking fluid in the low pressure cylinder when the ball valve is moved to open position. The unseating movement of the ball valve is limited by the stop 63 of the cylinder engaging the plunger. At this time the parts are in the position indicated in Figure 2 and the fluid pressure within the low pressure cylinder 2 is relieved by reason of the low pressure cylinder being placed in communication with the reservoir. As a result, continued downward movement of the piston rod causes the high pressure piston only to discharge braking fluid through the discharge port. When the piston rod is released, the coil springs 39 and 44 act to return the piston rod and the pistons, respectively, to their off position.

With the construction as shown, the plunger 53 is moved against the ball valve 51 when the pressure of the braking fluid in the high pressure cylinder is approximately 15 lbs. per square inch higher than the pressure of the braking fluid in the low pressure cylinder.

In the modification illustrated in Figures 5 and 6, the high pressure piston 64 is by-passed when in its off position by the passageway 65 preferably formed in the high pressure cylinder 66. Also the low pressure piston 67 is by-passed when in its off position by the passageway 68 formed in the low pressure cylinder 69. Furthermore, the piston rod 70 is fixedly secured to the high pressure piston and the low pressure piston preferably by having a press fit with the reduced portion 71 of the sleeve 72 of the high pressure piston and also by having the integral enlargement 73 abutting an annular shoulder formed at the upper end of the reduced portion 71 and held in engagement therewith by the sealing cup 74 and the annular spacer 75. The up-

per end of the spacer is abutted by the annular body 76 of the low pressure piston. The construction of the device for relieving the fluid pressure in the low pressure cylinder 69 is the same as that of Figures 1 to 4, inclusive, with the exception that the plunger 77 for unseating the ball valve is of a length such that the ball valve is seated when the parts are in off position. There is but one retracting coil spring 78 which operates upon the piston rod 70 to return the piston rod and the pistons to their off position.

In the off position of the parts, as illustrated in Figure 5, the high pressure cylinder 66 is in communication through the passageways 65 with the low pressure cylinder 69 and the low pressure cylinder 69 is in communication through the passageway 68 with the reservoir 79. The ball valve is seated to close the communication between the low pressure cylinder and the reservoir through the low pressure piston. Upon downward pull on the piston rod 70, the pistons will be moved downwardly in unison to practically immediately close the passageways 65 and 68 and to then cause braking fluid in the low pressure cylinder 69 to be discharged through the ports in the head of the high pressure piston 64 into the high pressure cylinder 66 and the braking fluid in the high pressure cylinder 66 to be discharged through the discharge port. However, when a predetermined pressure of the braking fluid in the low pressure cylinder is reached, the ball valve is unseated by the braking fluid in the low pressure cylinder and then when a higher predetermined pressure of the braking fluid in the high pressure cylinder is reached, the braking fluid in the high pressure cylinder acts upon the plunger 77 to move the same upwardly to hold the ball valve in open position, at which time the low pressure cylinder is completely relieved from fluid pressure except that of the hydraulic head of the braking fluid in the reservoir. As a result, during continued downward movement of the piston rod the high pressure piston 64 acts only to discharge the braking fluid, as illustrated in Figure 6.

Figure 7 illustrates another modification which differs essentially from the modifications of Figures 1 to 4, inclusive, and Figures 5 and 6 in forming the upper end of the piston rod 80 with the annular flange 81 for directly slidably engaging the plunger 82 for unseating the ball valve. In this case, a suitable sealing ring 83 is provided in an annular groove in the plunger 82 for engaging the annular flange 81 to prevent the escape of the braking fluid through the axial passageway in the piston rod and between the plunger and the annular flange. This sealing ring also functions in the same manner as the sealing ring 54 to oppose frictional resistance to the unseating movement of the plunger.

What I claim as my invention is:

1. A fluid pressure control device comprising a cylinder having a discharge port, a second cylinder of larger diameter than said first mentioned cylinder, a fluid reservoir, a piston slidable in said first mentioned cylinder, a second piston slidable in said second cylinder and movable with said first mentioned piston, said second piston having a passageway therethrough for placing said second cylinder and reservoir in communication, a valve movable relative to said second piston for closing said passageway, a piston rod for directly advancing said pistons from off position, said piston rod being movable axially relative to said first mentioned piston and having a passageway

for placing said cylinders in communication and a valve engageable with said first mentioned piston to close said last mentioned passageway and to directly move said pistons from off position, and a plunger engageable with said first mentioned valve in the off position of said piston rod to hold said first mentioned valve in open position, said plunger also being movable relative to said piston rod during the advance of the latter to permit said first mentioned valve to move to closed position and then to hold said first mentioned valve in open position under the fluid pressure created in said first mentioned cylinder.

2. A fluid pressure control device comprising a high pressure cylinder, a low pressure cylinder, 15 a reservoir, high pressure and low pressure pistons in said high pressure and low pressure cylinders, respectively, a piston rod for directly advancing said pistons from off position, said piston rod having a passageway in communication with said high pressure cylinder, said low pressure piston having a passageway therethrough for placing said low pressure cylinder in communication with said reservoir, a valve for controlling said last mentioned passageway, a plunger engageable with said valve and extending within said piston rod and subject to the pressure of the fluid within said piston rod passageway, and means between the side of said plunger and the encircling portion of said piston rod imposing a resistance to the movement of said plunger.

3. A fluid pressure control device comprising a high pressure cylinder, a low pressure cylinder, a reservoir, high pressure and low pressure pistons in said high pressure and low pressure cylinders, respectively, a piston rod for directly advancing said pistons from off position, said piston rod having a passageway in communication with said high pressure cylinder, said low pressure piston having a passageway therethrough for placing said low pressure cylinder in communication with said reservoir, a valve for controlling said last mentioned passageway, a plunger engageable with said valve and extending within said piston rod and subject to the pressure of the fluid within said piston rod passageway, and a sealing ring between the side of said plunger and the encircling portion of said piston rod frictionally engaging said plunger.

4. A fluid pressure control device comprising a high pressure chamber having a discharge port, a low pressure chamber for discharging fluid into said high pressure chamber, a reservoir, and a mechanism for placing said low pressure chamber in communication with said reservoir when a predetermined pressure is created within one of said chambers to relieve the fluid pressure in said low pressure chamber, said mechanism comprising a valve movable by the fluid in said one of said chambers, a dashpot plunger engageable with said valve, and an adjustable dashpot cylinder within which said plunger is slidable, said cylinder having a stop for limiting movement of said valve.

5. A fluid pressure control device comprising a high pressure chamber having a discharge port, a low pressure chamber for discharging fluid into said high pressure chamber, a reservoir, and a mechanism for placing said low pressure chamber in communication with said reservoir when a predetermined pressure is created within one of said chambers to relieve the fluid pressure in

5 said low pressure chamber, said mechanism comprising a valve movable by the fluid in said one of said chambers, a dashpot plunger engageable with said valve, an adjustable dashpot cylinder within which said plunger is slidable, said cylinder having a stop for limiting movement of said plunger, and adjustable spring means resisting movement of said plunger.

6. A fluid pressure control device comprising a high pressure cylinder, a low pressure cylinder, a reservoir, high pressure and low pressure pistons in said high pressure and low pressure cylinders, respectively, said low pressure piston having a passageway therethrough, a valve for controlling said passageway, means operable by the fluid in said high pressure cylinder for holding said valve in open position, a dashpot plunger controlling movement of said valve, a dashpot cylinder mounted on said low pressure piston and within which said plunger is slidable, and spring means mounted on said low pressure piston for resiliently resisting movement of said plunger.

7. A fluid pressure control device comprising a high pressure cylinder, a low pressure cylinder, 25 a reservoir having an opening, a closure member for the opening detachably secured to said reservoir, high pressure and low pressure pistons in said high pressure and low pressure cylinders respectively, and mechanism for placing said low pressure cylinder in communication with said reservoir when a predetermined pressure is created in one of said cylinders to relieve the fluid pressure in said low pressure cylinder, said mechanism comprising a valve movable by the fluid in said one of said cylinders, a dash pot plunger engageable with said valve, a dash pot cylinder within which said plunger is slidable, said cylinder being adjustably mounted on said low pressure piston, and spring means resisting movement of said plunger, said spring means also being adjustably mounted on said low pressure piston, said dash pot plunger, dash pot cylinder and spring means being located within said reservoir for ready accessibility through the opening 30 when said closure member is detached.

8. A fluid pressure control device comprising a high pressure cylinder, a low pressure cylinder, a reservoir, high pressure and low pressure pistons in said high pressure and low pressure cylinders respectively, said low pressure piston having a passageway therethrough for placing said low pressure cylinder in communication with said reservoir, a valve for controlling said passageway, said valve being movable to open position by the fluid in one of said cylinders, and means independent of the flow of fluid through said passageway for controlling the opening movement of said valve, said controlling means comprising a dash pot plunger engaging said valve and a dash pot cylinder slidably receiving said dash pot plunger.

9. A fluid pressure control device comprising low pressure producing means and high pressure producing means, a valve for relieving pressure of fluid in said low pressure producing means upon the attainment of a predetermined pressure in said low pressure producing means, adjustable spring means resisting movement of said valve, and stop means adjustable independently of said spring means for limiting movement of said valve.
